UNITED STATES PATENT OFFICE.

URA U. ULAM, OF MCKEESPORT, PENNSYLVANIA.

TIN-PLATE CATCHER.

1,196,619.

Specification of Letters Patent. Patented Aug. 29, 1916.

Application filed April 18, 1916. Serial No. 91,913.

To all whom it may concern:

Be it known that I, URA U. ULAM, a citizen of the United States, residing at McKeesport, in the county of Allegheny and State of Pennsylvania, have invented new and useful Improvements in Tin-Plate Catchers, of which the following is a specification.

The invention relates to a tin plate catcher, 10 and more particularly to the class of tension feed-out rollers for tin-plate machines.

The primary object of the invention is the provision of a feed-out roller of this character wherein the shaft supporting the same 15 in the tin-plate catcher will be driven under tension, the roller being loose thereon, and in this manner the tin-plate will be caught thereby in the catcher machine without the marking of the plate and also said plate will 20 be jerked from the rollers of the tinning machine instead of dragging it over the rollers, which results in damage to the sheet.

Another object of the invention is the provision of a feed-out roller of this character 25 wherein the construction thereof and its mounting in the tin-plate catcher is novel to assure the successful feed of the tin plates from the tinning machine so that the sheets will travel uniformly and the rollers also 30 travel therewith without slipping, thereby avoiding the marking of the sheets or the formation of a heavy edge thereto resultant from the slow feed of the plate from the rolls of the tinning machine.

35 A further object of the invention is the provision of a feed roller of this character which is simple in construction, readily and easily applied to the ordinary well known types of tin-plate catchers, thoroughly reliable and efficient in its purpose, strong, durable and inexpensive in manufacture.

Other objects will be in part obvious and in part hereinafter set forth.

The invention accordingly consists in the 45 features of construction, combination of elements and arrangement of parts which will be exemplified in the construction herein-after described, and the scope of the application of which will be indicated in the appended claims.

In the accompanying drawings; Figure 1 is a front elevation of a tin plate catcher in

position relative to a tinning pot and showing the improved feed-out rolls constructed in accordance with the invention applied; 55 Fig. 2 is a side elevation thereof; Fig. 3 is a fragmentary vertical transverse sectional view through one of the feed-out rolls; Fig. 4 is a sectional view on the line 4-4 of Fig. 1; Fig. 5 is an elevation of a modified form 60 of feed-out roll; Fig. 6 is a sectional view on the line 6-6 of Fig. 5; Fig. 7 is a vertical transverse sectional view through the roll.

Similar reference characters indicate corresponding parts throughout the several views of the drawings.

Referring to the drawings in detail, A designates the tinning pot which is of a proper width to receive two sets of upper 70 tinning rolls 10 and 11 respectively, while above and in line with each upper set of tinning rolls is a set of feed-out rolls 12 and 13 respectively, each being of any approved type. The bearings for one roll of each feed-out set are movable within yokes 14 and are yieldably pressed toward the stationary bearings of the other rolls of the set in any suitable manner and can be adjusted as usual. The yokes for the bearings are preferably mounted upon a frame having screw threaded corner supports 15 mounted upon the pot, thus providing for the adjustment of the yokes vertically by the nuts 16. Between the opposite yokes extend cross bars 85 17 to which are secured inclined guide fingers 18 and 19. The space between the guide fingers, by reason of the disposition thereof, tapers upwardly and directs the upper end of the rising sheet into the nip of the feed-out rolls.

Above and between the two sets of lower feed-out rolls is a single upper set of feed-out rolls, each comprising a hub 20, spokes 21 and a rim 22 which are integral with each other. The sheets are guided from each side into this upper or single pair of feed-out rolls by the outer guide fingers 23 which are bolted to cross bars 24 on the yokes, while the tubular guide 25 is mounted between the 100 fingers 23 in any suitable manner. The sheets rising from the upper feed-out rolls pass up between inclined guides 26 bolted or otherwise secured to the uppermost yokes.

After each sheet is thus fed upwardly between the guides it slides back from the feed-out rolls and down the inclined chute 27.

5 As the upper single pair of feed-out rollers handles the product from both lower pairs of feed-out rollers it is desirable that this upper pair should be driven at a higher rate of speed than the lower pair and there 10 are provided suitable connections for so driving the upper rollers at higher speed, and these connections are made with a shaft 28 which supports the upper single pair of feed-out rollers which are mounted upon the 15 shaft in a manner presently described. The hub 20 of each upper pair of feed-out rollers is loosely engaged upon the shaft 28, while fixed to the latter at opposite sides of the hub and spaced therefrom are collars 29 20 which have mounted therein eccentrically disposed pins 30 to each of which is connected one end of a coiled tensioning spring 31, the same surrounding a sleeve 32 loose upon the shaft 28 between the hub 20 and the collar 29 adjacent thereto, while the opposite end of the spring 31 is connected to a pin 33 mounted eccentrically in each upper feed-out roller preferably in one spoke 21 thereof. Each collar 29 is fixed upon the shaft 28 30 through the medium of a set screw 34.

Fastened on either side of each uppermost feed-out roller is a ratchet toothed rim 35, while pivoted to the cross bar 24 supporting the fingers 23 is a ratchet pawl 36, the latter 35 being adapted to engage the ratchet rim 35 so as to prevent recoil of the springs 31 on the slackening thereof when the plate has been jerked from the lower feed-out roll under the tensioning of the spring 31 connected to the uppermost feed-out roll.

Passed between a pair of the spokes 21 adjacent each other is an upwardly arched bar 37 which is also fastened to the set screws 34 and this bar serves to act as a 45 safety device to allow a certain amount of tension of the springs coacting with the upper set of feed-out rolls.

In Figs. 5, 6 and 7 there is shown a slight modification of the invention wherein each 50 uppermost feed-out roll comprises a wheel body 38 having a hub portion 39 for loosely surrounding the shaft 40 to which is fixed a collar 41 which holds the feed-out roller against longitudinal displacement, in one 55 direction, on the shaft, while fixed to the shaft at the opposite side of the wheel body 38 is a disk 42 having mounted therein eccentrically of the same a pin 43 which works within a slot 44 formed in the wheel body 38, and to this pin is connected one 60 end of a coiled tensioning spring 45 which is housed within the wheel body 38 and has its opposite end fixed to a pin 46 mounted eccentrically on the wheel body. Bolted or

otherwise secured exteriorly to one side of 6 the wheel body 38 is a ratchet toothed rim 47 with which is adapted to engage a ratchet pawl, the same being the equivalent of the pawl 36 hereinbefore described and is mounted in a manner identical thereto so as 70 to avoid any recoil of the spring 45 when tension is relieved therefrom.

When the sheets are taken in by the upper single set of feed rollers the springs acted upon by the shaft become tensioned by reason of the fact that the shaft is driven at a faster rate of speed than the roller and when the sheets ride off of the lower feed-out rollers these upper feed-out rollers which are now tensioned will suddenly jerk the 80 sheets from the lower feed-out rollers, thereby avoiding the dragging of the sheets or the marking of the same by reason of a drag or other injury to the sheets, because, due to the mounting of the upper feed-out rollers, 85 the same are free to move slower than the speed of rotation of the shafts supporting them as the springs take up the increased speed of the latter by the tensioning of the springs, and when the sheets are about to 90 run from the other rollers, due to the tensioned condition of the springs, the upper feed-out rollers will jerk the sheets therefrom, thus avoiding injury to the sheets resultant from the dragging thereof. 95

From the foregoing description, taken in connection with the accompanying drawings, the construction and operation of the herein described device will be readily apparent and, therefore, a more extended explanation 100 has been omitted.

Having thus described my invention, I claim:

1. A catcher roll for tin plate catchers comprising a wheel like body adapted to be 105 loosely mounted upon one of the shafts of the catcher, a ratchet wheel exteriorly of the body and movable therewith, a stationarily mounted pawl engageable with the ratchet gear, a collar adapted to be fixed to 110 said shaft, and tensioning means connected with the wheel body and the said collar.

2. A catcher roll for tin plate catchers comprising a wheel like body adapted to be 115 loosely mounted upon one of the shafts of the catcher, a ratchet wheel exteriorly of the body and movable therewith, a stationarily mounted pawl engageable with the ratchet gear, a collar adapted to be fixed to said shaft, tensioning means connected with the 120 wheel body and the said collar, and means for limiting free movement of the connection between the wheel body and the said tensioning means.

3. A catcher roll for tin plate catchers 125 comprising a wheel like body adapted to be loosely mounted upon one of the shafts of the catcher, a ratchet wheel exteriorly of the

body and movable therewith, a stationarily mounted pawl engageable with the ratchet gear, a collar adapted to be fixed to said shaft, tensioning means connected with the wheel body and the said collar, means for limiting free movement of the connection between the wheel body and the said tensioning means and a sleeve adapted to loosely

surround said shaft and support said tensioning means.

In testimony whereof I affix my signature.

URA U. ULAM.
